UNITED STATES PATENT OFFICE.

CHARLES G. ROBINSON, OF PITTSBURGH, PENNSYLVANIA, ASSIGNEE TO WHEELING STEEL CASTING COMPANY, OF WHEELING, WEST VIRGINIA, A CORPORATION OF WEST VIRGINIA.

APPARATUS FOR MAKING INGOT-MOLDS.

1,110,348.

Specification of Letters Patent. Patented Sept. 15, 1914.

Application filed September 10, 1913. Serial No. 789,164.

To all whom it may concern:

Be it known that I, CHARLES G. ROBINSON, a citizen of the United States, residing at Pittsburgh, in the county of Allegheny and State of Pennsylvania, have invented a new and useful Improvement in Apparatus for Making Ingot-Molds, of which improvement the following is a specification.

My invention relates to apparatus for making ingot molds, and to ingot molds.

Heretofore, so far as I am aware, formers, molds or flasks for the manufacture of ingot molds have been made in separable parts which were bolted or otherwise securely fastened together.

The objects of my invention are two-fold; first, to produce an apparatus for molding or producing a unitary or one-piece cast steel ingot mold, the said apparatus comprising a unitary or one-piece cast steel former having cores so disposed therein as to form an ingot mold having stripper lugs or other projections thereon, the said cores being so disposed in said former as to permit the ready stripping or removal of the former from the ingot mold and, second, to produce a unitary or single piece cast steel ingot mold having stripper lugs or other projections thereon.

A further object of my invention is to produce an ingot mold which has been uniformly cooled exteriorly and interiorly. And having interior surfaces possessing the highest degree of fineness due to the fact that no part of the core is liable to be fused by or to the molten metal, thus enabling the ready discharge of the ingot therefrom and at the same time producing an ingot having even and smooth exterior surfaces.

A still further object of the invention is to enable the ready escape or discharge of gas or gases from the interior and exterior surfaces of the ingot mold during the pouring of the ingot and after the pouring operation has been completed.

I attain these several objects by means of the apparatus hereinafter more specifically described, reference being had to the accompanying drawings forming part hereof, in which;

Figure 1 is a plan view of the ingot mold; Fig. 2 is a central section through lines 2-2 of Fig. 1; Figs. 3 and 4 are respectively plan and front views of the core blocks 7. Fig. 5 is a plan view of a plate

casting funnel and runners and a sectional plan of four ingot mold formers. Fig. 6 is a vertical section through lines 6-6 of Fig. 5. Fig. 7 is a vertical section of the ingot mold former taken at right angles to Fig. 2. Fig. 8 is a transverse section on lines 8-8 of Figs. 2 and 7.

Referring to said drawings, 1 is the usual bottom plate whereon are disposed in any suitable manner ingot mold formers or flasks 2, 3, 4 and 5. The said ingot mold formers comprise a unitary or single piece solid cast steel flask, the wall *a* of which is provided with trunnions *b*, the said trunnions being disposed at the sides of said flask in the usual way, whereby the said mold or flask may be readily turned. The wall of said flask is provided with a series of vents or openings *c* which extend from the air spaces *d* to the exterior as shown in Fig. 7. The said air spaces are provided by longitudinally disposed channels in opposite sides of the chill, the upper ends of the channels remaining open to form the lugs 8 on opposite sides of the ingot mold. Core blocks 7 are fitted in the channels toward the upper ends thereof and serve to form the lower sides of the said lugs 8. Below the core blocks 7 the mouths of the channels are closed by the vertically disposed cores or walls 6 which are preferably formed of sand, the said cores 6 being set into the channels so that the inner surface of the mold former or chill is smooth. Within said chill or outer wall 1 I insert a hollow core 10 which is preferably made of sand and preferably in sections as shown in the drawings. The said core 10 is positioned centrally within the chill so as to be spaced from the inner walls of the chill a distance corresponding to the proposed thickness of the walls of the ingot mold. The upper end of the core 10 is capped by a ring 11. The said ingot mold formers are disposed on the plate 1 and are connected with a centrally disposed casting funnel 12 by means of the usual runners 13-13 which enter the said formers preferably by the double conduits 14 at the bottom thereof.

I have called the outer flask or mold "a former" throughout the specification in order to distinguish it from the ingot mold made therein. This former may be made in the usual way castings of its size are produced.

Having described my invention, what I claim and desire to secure by Letters Patent is:

1. An apparatus for casting unitary steel ingot molds having stripper lugs formed thereon, said apparatus including a unitary metal mold, a centrally disposed core, and core blocks disposed within said mold near the upper end and on opposite sides thereof and adapted to form the under side of the lugs on the ingot mold, the remaining portion of the said lugs being formed by the walls of said unitary metal mold.
  2. In an apparatus for making ingot molds, the combination of an outer wall or mold, a core centrally disposed therein, core blocks disposed in the upper portion of said mold, vertically disposed cores arranged in said mold between the inner wall of said mold and the first mentioned core to form air spaces within the wall of said mold on opposite sides, said mold having vents leading from the said air spaces to the exterior.
  3. In an apparatus for making ingot molds, the combination of an outer wall or mold, a core centrally disposed therein, core blocks disposed in the upper portion of said mold, vertically disposed cores arranged in said mold between the inner wall thereof and said first mentioned core to form an air space in the wall of said mold on each of the opposite sides, said air spaces extending from said core blocks to the lower end of said mold, and said mold having vents leading from said air spaces to the exterior.
  4. In an apparatus for making ingot molds, the combination of an outer wall or mold, a core centrally disposed therein, core blocks disposed in the upper portion of said mold, vertical cores disposed in supporting relation to said core blocks and arranged between the inner wall of said mold and the first mentioned core.
  5. In an apparatus for making ingot molds, the combination of a unitary mold
- of cast steel, a core centrally disposed therein forming the cavity in which the ingot is cast, core blocks disposed in the upper portion of said cast steel mold constituting formers for the under surface of the strip-
per lugs on said ingot mold, vertically disposed cores arranged within said cast steel mold between the outer wall of the centrally disposed core and the inner wall of the cast steel mold whereby spaces are formed within the latter for the reception of the molten metal forming the ingot mold, said cast steel mold having vents leading from said spaces to the exterior.
6. In an apparatus for molding ingot molds having stripper lugs thereon, a unitary or single-piece cast steel former having cavities in the sides thereof for the reception of the stripper lugs, and cores so disposed in said former as to allow the casting of the ingot mold therein, permitting said lugs to contract uniformly with the remaining portion of said ingot mold.
7. An apparatus for casting unitary steel ingot molds having stripper lugs formed thereon, said apparatus including a unitary metal mold having longitudinally disposed channels in opposite sides thereof, a centrally disposed core, core blocks disposed in said channels near the upper end thereof and adapted to form the underside of the lugs on the ingot mold, the remaining portion of the said lugs being formed by the walls of said unitary metal mold, and vertically disposed cores adapted to close the sides of the channels adjacent to the ingot mold.

In testimony whereof, I have hereunto signed my name in the presence of two subscribing witnesses.

CHARLES G. ROBINSON.
